UNITED STATES PATENT OFFICE.

JOHN J. CONVERY, OF NEW YORK, N. Y.

TELEPHONE ATTACHMENT.

1,216,776.

Specification of Letters Patent. Patented Feb. 20, 1917.

Application filed July 25, 1916. Serial No. 111,245.

To all whom it may concern:

Be it known that I, JOHN J. CONVERY, a citizen of the United States, residing at New York, in the county of New York and State 5 of New York, have invented certain new and useful Improvements in Telephone Attachments, of which the following is a specification, reference being had therein to the accompanying drawing.

10 This invention relates to a receiver-holding and hook-operating attachment for telephones.

It contemplates, among other objects, the provision of means for holding the receiver 15 in position against the ear of a person using a telephone and in such a way that free use of both hands will be permitted.

Considerable difficulty has been experienced in the use of telephones by reason of 20 the fact that persons using them are too close up, too far away from, or do not speak directly into the transmitter. It is one of the objects of this invention to remedy these 25 defects by positioning the receiver with relation to the transmitter so that the best results may be obtained.

A further object is so to arrange the attachments and operative parts of the device 30 with relation to the telephone that it will not detract from or interfere with the normal 35 and usual manner of operation, and thus avoid objections made generally to the use of such attachments.

The simplicity of this device, its few parts, 35 the manner of operatively connecting it with the telephone hook, and other objects and advantages, will in part be obvious, and in part be made clear in the description which follows.

40 Drawings are hereto appended which illustrate two possible embodiments of the invention, and in which:

Figure 1 is a view in side elevation, showing one form of the device attached to a desk 45 telephone of well-known type:

Fig. 2 is a fragmentary view in front elevation;

Fig. 3 is a sectional view on lines 3—3, Fig. 1;

50 Fig. 4 is a top plan view of the device illustrated in Fig. 1, a portion being broken away;

Fig. 5 is a side elevation, partly in section of a portion of the device;

55 Figs. 6 and 7 are fragmentary plan views, respectively, of coöperating parts;

Fig. 8 is a detached view in side elevation of a part;

Figs. 9, 10, 11 and 12 are views in top plan, 60 vertical section, end elevation, and cross section, respectively, of one of the components;

Fig. 13 is a top plan view of another embodiment; and

Figs. 14, 15 and 16 are similar views of 65 slightly modified forms of alternative component parts.

In these drawings, the numeral 1 designates, generally, a telephone, comprising a body or pedestal 2, a transmitter 3, a receiver 4, and an operating hook 5.

70 The devices which comprise my invention are adapted to be associated with the telephone and may be said to comprise a supporting means 6, a trigger carrying extension bracket 7, and a receiver-supporting 75 arm 8, together with connections and associated components which will be hereinafter described.

The supporting means, when used in connection with a telephone of the desk type, 80 comprise preferably a clamping element having coöperating parts 9 and 10 connected at one end, as by a hinge 11. At the other end it is provided with a locking means 12. Intermediate their ends, the coöperating 85 parts of the clamping means are hollowed or formed so as to embrace the pedestal of the telephone and may be provided with a cushioning lining 13. The locking means for said clamp, as here shown, comprise a 90 stem 14, pivotally connected at one end to a lug 15, on the portion 12 of the clamping bracket, its other end being threaded for the reception of a thumb-screw 16 adapted to bear against a lug 17 carried by the other 95 component of the clamping member.

Mounted upon a portion 10 of the clamping member is an arm 19 having at its upper end a reduced portion 20 and a projection 21. This is adapted to be embraced by a 100 collar 22 having a notch 23 adapted to engage the projection 21, as best seen in Figs. 6 and 7.

The collar 23 is formed on the free end of an angulated extension-bracket 24 which has 105 mounted intermediate its ends a trigger 25. This trigger has at one end an offset portion 26 and an extended portion 27, and is mounted intermediate its ends upon a pivot 28 carried by the extended portion of the angulated arm. The other end of the trigger 25 is provided with a resilient means 30, such 110

as a spring, secured to a knob 31 on the arm and a corresponding projection 32 on the end of the trigger.

The purpose of this trigger is to hold 5 down the hook of the telephone while the receiver is off the hook and is seated in the bracket. To this end, there is provided a projection 33 carried by a collar 34 having a threaded stem 35 which is adapted to 10 pass through an opening 36 in the hook and be held into engagement therewith by a collar 37. The offset portion 26 of the trigger arm by pressing against the projection 33 normally holds the hook down in its 15 lowermost position.

Means for connecting the receiver-supporting-arm 8 to the extended arm 7 are also provided and, as here shown, comprise a clamping instrumentality having two coacting portions 41 and 42 in engagement at one end and hollowed out at their opposite end for the reception of the angulated arm 24. Intermediate the ends of these clamping members, there is provided a locking means 20 which constitutes an eye 42' adapted to hold and surround one end of the receiver-supporting-arm 8. Upon this eye, there is mounted a stem 45 threaded at its free end and passing through openings 46 and 47 25 in the clamping members. A thumb-nut 48, disposed on the threaded end of this stem, is adapted to hold the loop in engagement with the free end of the receiver-supporting-arm and, at the same time, force 30 the clamping members into engagement with the end of the angulated extension arm.

Upon the outer end of the receiver-supporting-arm there is mounted a holding 40 member. This member is preferably in the form of a semi-circular extension hollowed out in the center and having opposed faces 50 and 51 which permit the insertion therebetween of an extended collar 52 which is 45 usually found upon the end of the receiver.

The receiver-supporting arm may be square (as shown in Fig. 15) or rounded (as shown in Fig. 16), and it has been found desirable, in some instances, to provide it with a bend or offset as at 53, and best seen in Figs. 15 and 16. This deflection is for the purpose of holding the receiver in more intimate contact with the ear of the operator when using the telephone.

55 For use in connection with a telephone of the wall-type, there is provided a supporting bracket comprising a base 54 adapted to be secured to the wall or to the back of the telephone in any desirable manner, as 60 by screws 56. Upon this base, there is mounted a support 57, hollowed out internally for the reception of a portion 58 of an angulated extension arm 59. This may be held in position suitably, as by a screw 60. 65 In this construction, the trigger mechanism

is generally mounted upon a projection 61 which is in alignment with the portion 58 of the arm, while the receiver-supporting-arm is mounted upon the extended portion 59 in angular relation to portion 58, as before described. This trigger mechanism is normally held in engagement with projection 33 carried by the hook as through spring 64 secured to one end of the trigger, and at the other end secured to a projection 65 mounted on the angulated support. 75

In order to prevent accidental tipping of a telephone of the desk-type, there is provided in conjunction with the apparatus just described a bracing member comprising a 80 clamping instrumentality having two portions 66 and 67 provided with eyes 68 and adapted to be secured around the pedestal of the telephone as by screws 69 disposed in said eye and adapted to draw said portions together in clamping engagement with the base. Upon one of these members there are mounted extended arms 70 and 71 in spaced apart angular relation and provided with feet 72 adapted to normally rest at the 90 base level of the telephone.

In operation, the receiver-supporting arm 8 is adjusted so that, when in use, the operator by pressing his ear against the receiver will be in the proper position with relation 95 to the transmitter most effectively to use the telephone. In this position, it is only necessary to move the trigger toward the base of the telephone, thus permitting the projection 33 to ride up over the offset portion 26 of the trigger and close the circuit. When the operator is through using the telephone, by pressing down on the hook, the offset portion 26 thereof will ride up over the projection 33 and hold the hook down, opening 100 the circuit and rendering the telephone inoperative.

From the foregoing, it will be apparent that I have provided a convenient and efficient means for maintaining a receiver, of 110 a telephone in proper relation to the transmitter; and wherein both hands of the operator are free during the transmission and reception of messages; and which will not interfere with the normal working of the 115 telephone in any way.

While I have disclosed the invention in the two embodiments herein illustrated, it will be evident that many changes in the construction and general arrangement of the parts may be made, without departing from the spirit of the invention or sacrificing its chief advantages.

What I claim is:—

1. A receiver-supporting and hook-operating attachment for telephones, comprising a support adapted to be operatively associated with a telephone, an extension-arm disposed on the support, a mounting disposed on the extension-arm and comprising 125

co-acting clamping-members, an eye having a stem passing through the clamping-members, a receiver-supporting member mounted in said eye, means for effecting pressure between the clamping-members, the eye, and the extension-arm, and trigger-mechanism disposed on the arm and adapted normally to engage a hook on the telephone.

2. A receiver-supporting and hook-operating attachment for telephones, comprising a supporting-bracket adapted to be operatively associated with the telephone, an angulated extension-arm disposed on the bracket, a receiver-supporting member 15 mounted on the angulated arm, a trigger mechanism disposed on the arm and adapted normally to engage a hook on the telephone, and means for adjustably supporting the member on the angulated arm and 20 comprising co-acting clamping-members and an eye having a stem passing therethrough and adapted to embrace a portion

of the receiver-supporting member and be pressed into engagement therewith.

3. A receiver-supporting and hook-operating attachment for telephones, comprising a supporting bracket adapted to be operatively associated with the telephone, an angulated extension-arm disposed on the bracket and adjustable horizontally and vertically with relation to said telephone, a receiver-supporting member mounted on the arm, means for locking the member to the arm comprising co-acting clamping-members adapted to embrace a portion of the 30 arm, and an eye adapted to embrace a portion of the receiver-supporting member and having a stem passing through the clamping members, and trigger-mechanism disposed on the arm and adapted normally to engage 35 a hook on the telephone.

In testimony whereof I affix my signature.

JOHN J. CONVERY.
